UNITED STATES PATENT OFFICE

2,683,035

BOWLING PIN RESETTING APPARATUS

Russell C. Roshon, Memphis, Tenn.

Application June 1, 1951, Serial No. 229,346

1 Claim. (Cl. 273—45)

1

This invention relates to bowling alleys of the miniature or table type where balls are rolled and pins reset from the playing end of the game board or alley, and in particular an improved resetting device for a miniature bowling alley wherein the tenpins are reset by pulling on a knob.

The purpose of this invention is to provide an improved miniature bowling alley wherein the tenpins are readily set up from the bowling end of the alley.

Another object of the invention is to provide means for connecting tenpins of a miniature bowling alley to a common drum whereby the pins are instantly set up in correct positions by pulling a single cable or cord.

A further object of the invention is to provide an improved miniature bowling alley which is of a simple and economical construction.

With these and other objects and advantages in view the invention embodies an elongated game board or bowling alley with tenpins positioned over openings through the far end of the alley and actuated to set up positions by cords extended through the pins and openings in the alley to a drum which is actuated from the playing end of the alley.

Other features and advantages of the invention will appear from the following description taken in connection with the drawings wherein:

Figure 1 is a plan view of the improved miniature bowling alley.

Figure 2 is a longitudinal section, on an enlarged scale taken on line 2—2 of Figure 1 through the end of the alley on which the tenpins are positioned and illustrating the connections of the pins to an operating drum.

Figure 3 is a sectional plan taken on line 3—3 of Figure 2 also showing the end of the alley in which the pins are positioned, and with the intermediate part of the alley broken away.

Figure 4 is a detail showing a section through the alley taken on line 4—4 of Figure 2.

Figure 5 is a similar section taken on line 5—5 of Figure 2.

Referring now to the drawings wherein like reference characters denote corresponding parts the improved miniature bowling alley of this invention includes a floor 10 having ball runways 11 and 12 at the sides, tenpins 13 connected by cords 14 to a drum formed with spaced bars 15, a pull cord 16 having a knob 17 on the outer end, a V-shaped guide 18 positioned on an inclined panel 19, and a bumper 20.

The floor 10 is supported by transverse beams 21 on side rails 22 and 23 and one end of the

2

alley is provided with extensions 24 which are attached to the rails 22 and 23 by plates 25 and 26 with screws 27.

The transverse beams 21 are provided with recesses 28 and 29 and elongated panels 30 and 31 with molding strips 32 and 33 on the panel 30 and 34 and 35 on the panel 31 are positioned in the recesses thereby forming ball runways as indicated by the numerals 11 and 12 at the sides 10 of the alley or floor. Side panels 36 and 37 are positioned beyond the ball runways for retaining the balls on the alley.

The playing end of the alley is provided with a supporting panel 38, having an opening 39 15 therein in which the pull cord 16 extends and the baffles 40 and 41 extend upwardly from the panel 38 to provide stops for balls in the runways 11 and 12.

The far end of the floor of the bowling alley is 20 supported on a beam 42 the upper corner of which is provided with a recess 43 and the inclined panel 19 is positioned with the lower edge held in the recess 43 and the upper edge supported on a strip 44 carried by the rear wall 45 of the bowling alley. 25 A door 46 is attached to the lower end of the panel 45 by hinges 47 whereby access is provided to the tenpin cord actuating drum 15 below the alley.

The guide 18 which is provided with sloping edges 48 and 49 is positioned on the sloping member 19 and after the balls strike the tenpins and engage the bumper 20 they roll on the inclined edges 48 and 49 by which they are directed into the ball runways 11 and 12.

The bumper 20 is positioned between side walls 50 and 51, the lower edge of the bumper resting 35 upon the inclined panel 19 and the upper edge being secured to a cleat 52 extended between the side walls 50 and 51 and secured to the cover panel 53.

The bumper 20 is formed with a backing plate 40 54 and resilient material, as indicated by the numeral 28 is held in position thereon by an outer covering 55.

As illustrated in Figure 2 the bars 15, forming the actuating drum are carried by end sections 45 56 and 57 which, as shown in Figure 4 are journaled in the lower ends of bearing blocks 58 and 59 by bolts 60 and 61, the outer ends of which are provided with lock nuts 62 and 63, respectively.

Also as illustrated in Figure 2 the cords 14, extended from the tenpins 13 are secured to one of the bars of the drum, which is indicated by the numeral 64 by thumb nuts 65 on screws 66 which extend through the bar 64. The opposite ends 50 55 of the cords 14, which extend through openings

67, in the tenpins, are secured in recesses 68 in the upper ends of the pins by tying knots as indicated by the numeral 69 on the ends of the cords.

In the illustration, as shown in Figure 2, the cords 14, to the tenpins, are shown in tension and it will be appreciated that when the pull cord 16 is released a spring 70, attached to the drum at a point 71 and to a block 72 of the frame, reverses the rotation of the drum whereby the cords 14 are released so that sufficient slack is provided in the cords to permit the tenpins to be knocked over by the ball.

The drum is also provided with a segment 73 which is provided with a groove 74 in which the pull cord 16 is positioned and the end of the cord is secured to the segment by a screw 75.

The lower edge of one of the transverse beams 21 may be provided with a guide block 76, and the guide block 76 is provided with an opening 77 through which the pull cord 16 extends whereby the cord or cable 16 will be prevented from shifting from side to side.

The bearing blocks 58 and 59 are attached to the transverse beam 42 by screws 78, as shown in Figure 4.

The game board or alley 10 is provided with a plurality of openings 79 positioned to correspond with the triangular position of tenpins on a bowling alley and as the pins are drawn to upright positions they are correctly positioned on the alley. The bars of the drum may have arcuate outer surfaces.

It will also be understood that grooves or comparatively small troughs may be provided in the surface of the inclined panel 19, and particularly at the edges thereof to facilitate guiding the balls into the runways 11 and 12 at the sides of the alley and the position and arrangement of the member 18 may be changed to prevent the balls rebounding or bouncing backwardly to strike the pins from the rear.

It will be understood that modifications may be made in the design and arrangement of the parts

without departing from the spirit of the invention.

What is claimed is:

In a bowling alley, the combination which comprises an elongated panel having troughs at the sides, a bumper at one end and ten openings positioned in a triangle extended therethrough and positioned on the end of the panel on which the bumper is positioned, a transversely disposed drum having spaced parallel bars carried by end sections and positioned below the end of the panel in which the ten openings are provided, bearing blocks depending from sides of the panel and spaced from the end through which the openings extend, bolts extended through the end sections of the drum and into the bearing blocks for journaling the drum in the alley, a segment carried by the bars of the drum, a cable trained over the segment and extended to the end of the panel opposite to that in which said openings are positioned, gripping means on the end of the cable for drawing the cable to operate the drum, a spring connected to the drum and alley for returning the drum upon release of the cable gripping means, ten pins having longitudinally disposed bores therethrough positioned over the openings through said panel, and cords extended from a bar of said drum through the openings in the panel, through said ten pins, and secured to the upper ends of said ten pins, the bars of the drum having arcuate outer surfaces, and said cords connecting the ten pins to the drum being positioned to be wrapped on said arcuate outer surfaces in response to an outward pull on said cable.
